PACKING CASE

Clifford D. Fallert, St. Louis, Mo., assignor to
Robert Gaylord, Incorporated, a corporation
of Missouri

Application March 18, 1933. Serial No. 661,544

6 Claims. (Cl. 229—43)

My invention relates to a packing case formed of fiberboard or similar bendable material for use in shipping or storing merchandise requiring greater protection than is afforded by the ordinary fiberboard cartons.

The object of my invention is to so construct a case as to provide both vertical and lateral bracing, preferably without the use of reinforcing strips or bars of wood or the like.

10 In the accompanying drawing, which illustrates one form of packing case made in accordance with my invention, Figure 1 is a perspective view of one end of the case, one of the cover members being shown in raised position; Figure 2 is a perspective view of a portion of one of the cover members; Figure 3 is an end elevation; Figure 4 is an enlarged section taken on the line 4—4 of Figure 5; Figure 5 is an enlarged section taken on the line 5—5 of Figure 3; and Figure 6 is a detail view showing the slot in one of the end panels.

The bottom 1, side walls 2, and cover sections 3 and 4 are formed of an integral sheet of fiberboard. End flaps 5 and 6 are carried by the bottom and side walls, respectively. Secured to the end flaps by any suitable means, such as staples 7, are the end panels 8. As these panels do not require bending they may be made of heavier fiberboard than the remainder of the case. The upper ends of the flaps 6 are left unattached to the panels for a sufficient distance to receive the end flanges of the cover sections hereinafter to be described. Formed in the upper edge of each of the end panels is a slot 9 (Figure 6).

35 The cover section 3 is provided with a side flange 10 and a pair of end flanges 11. Each end flange is secured to the adjacent end flange by staples 12 passing through the side flange and a tab 13 on the end flange. Carried by the cover section 4 are end flanges 14 the ends of which are secured by staples 15 to tabs 16 of a strut member U-shaped in cross section. This strut member is integral with the cover section 4 and comprises a downwardly extending plate 17 and an upwardly extending flange 18 spaced a sufficient distance apart by a connecting web 19 to receive the flange 10 and tab 13 between them. On the ends of the flange 18 are tabs 20 bent at right angles to the flange and lying between the flanges 11 and the end panels when the cover sections are in closed position. The function of the tabs 20 is to prevent the ends of the flange 18 from being disengaged from the slots 9 by flexure of the strut. The flanges 11 are enabled

55 to more effectively perform their function of re-

taining the tabs 20 due to the fact that their outer ends are positioned between the end panels and the flaps 6.

In using my packing case, after the contents have been placed in the case, the cover section 4 is first closed, as shown in Figure 1, the ends of the channel members entering the slots 9 and the tabs 20 lying against the outer faces of the end panels. The cover section 3 is next closed, the flange 10 entering the channel of the strut 65 members. The flange 10 thus acts as a filler, increasing the resistance of the struts to both vertical and longitudinal pressure. After the cover is closed, it may be sealed in any suitable manner, as by means of a metal band 21 passing 70 around the case and having its ends secured together by a seal 22. In case this method of sealing is used, the upper strand of the band should lie in a groove 23 formed in the manner described in my co-pending application of even date here- 75 with.

Having fully described my invention, what I claim as new and desire to secure by Letters Patent of the United States is:

1. A packing case comprising side and end walls, said end walls being provided with slots, cover sections hinged to said side walls, a channel member carried by one of said cover sections and entering said slots, and a flange on the other cover section engaging said channel member and forming therewith a reinforcing brace.

2. A packing case comprising side and end walls, said end walls being provided with slots, cover sections hinged to said side walls, a channel member carried by one of said cover sections and entering said slots, said channel member being provided at its ends with portions overlapping the outer faces of the end walls, a flange carried by the other cover section engaging said channel member, and means on said last named 90 cover section for holding said overlapping portion in position.

3. A packing case comprising side and end walls, said end walls being provided with slots, cover sections hinged to said side walls, a channel member carried by one of said cover sections and entering said slots, said channel member being provided at each end with a tab lying against the outer face of the adjacent end walls, a side flange carried by the other cover section 100 and engaging said channel member, and end flanges on said last named cover section, said end flanges being attached to the side flange and covering said tabs.

4. A packing case comprising side walls and 110

cover sections hinged thereto, said side walls being provided with flaps, end panels attached to said flaps, said end panels being provided with slots, a channel member carried on one of 5 said cover sections and entering said slots said channel member being provided at each end with a tab lying against the outer face of the adjacent end panel, a side flange on the other cover section engaging said channel member, 10 and end flanges on said last named cover section and overlying said tabs, said end flanges each being attached at one end to said side flange and projecting under one of the flaps at the other. 15 5. A packing case comprising side walls and cover sections hinged thereto, end walls provided with slots, a channel member integral with the inner edge of one of the cover sections and entering said slots; said channel member consisting of a downwardly extending plate 20 consisting of a downwardly extending plate, an

upwardly extending flange, and a connecting web; and a flange on the other cover section extending between the plate and said first named flange.

6. A packing case comprising side walls and cover sections hinged thereto, end walls provided with slots, a channel member integral with the inner edge of one of the cover sections and entering said slots; said channel member consisting of a downwardly extending plate provided at each end with a tab, an upwardly extending flange also provided at each end with a tab, and a connecting web; a side flange on the other cover section extending between the plate and the first named flange, and end flanges, 85 on the cover sections, those of one section being attached to the first named tabs and those of the other section overlying the second named tabs. 90
